UNITED STATES PATENT OFFICE.

CHARLES A. STUART, OF KENOSHA, WISCONSIN, ASSIGNOR TO SIMMONS COMPANY, OF KENOSHA, WISCONSIN, A CORPORATION OF DELAWARE.

DESIGN FOR A BEDSTEAD END.

56,714.

Specification for Design.

Patented Nov. 30, 1920.

Application filed March 8, 1920. Serial No. 364,299. Term of patent 14 years.

To all whom it may concern:

Be it known that I, CHARLES A. STUART, a citizen of the United States, residing at Kenosha, in the county of Kenosha and State of Wisconsin, have invented a new, original, and ornamental Design for a Bedstead End, of which the following is a specification, reference being had to the accompanying drawing, forming part thereof.

The figure is a perspective view of the foot end of a bedstead embodying my new design.

The salient features of this design are the continuous post and top rail with scalloped corners, the central panel having the char-

acteristics set forth in my co-pending application, Design No. 1964, and the pair of somewhat closely spaced vertical filler tubes located on either side of the central panel, substantially midway between the latter and the corner post.

My design is of especial value where the frame members of the bedstead end frame are constructed of metallic tubing.

I claim:

The ornamental design for a bedstead end, substantially as shown and described.

CHARLES A. STUART.
